DEODORIZER AND ANTISEPTIC DEVICE

Cornelius W. O'Reilly, Kew Gardens, N. Y.

Application July 24, 1934, Serial No. 736,756

2 Claims. (Cl. 4—222)

This invention relates to improvements in antiseptic dispensers and relates more particularly to devices of the type which are used in lavatories in association with urinals and bowls.

- 5 Devices of this character are provided with reservoirs or tanks which contain an antiseptic and deodorizing fluid, with outlets through which the fluid drips into the urinal or bowl, and sometimes with an air deodorizing or fumigating element.
- 10 Considerable waste is caused by the fact that the fluid drips continuously for twenty-four hours per day while generally it is needed only during certain hours, as during business hours when used in an office building lavatory, or during certain
- 15 hours of the evening when used in the lavatory of a theatre. Furthermore, considerable difficulty has heretofore been experienced with such devices in that the drip of the fluid and the operation of the air purifier or deodorizer sometimes provided on such devices are not maintained at a constant rate but vary in accordance with the amount of fluid in the tank or reservoir. Thus when the reservoir is substantially full the drip of the fluid through the outlet is rather rapid or
- 20 constant and the air deodorizer operates fairly satisfactorily, but as the level of the fluid in the tank declines the drip of the fluid is not maintained at a constant rate and the deodorizer operates erratically, if at all.
- 25 30 It is accordingly an object of this invention to provide an antiseptic dispenser which may be adjusted to permit the fluid to drip through the dispensing outlet of the device only during certain predetermined periods of the day.
- 35 A further object is the provision of a device of the above character which will operate in a satisfactory manner and at a constant rate regardless of the level of the fluid in the tank and which when once adjusted will operate automatically and
- 40 45 without the need for constant attention and supervision.

Another object is to provide an improved device of the above character having an antiseptic fluid tank or reservoir connected to a plurality of dispensing outlets through which the fluid may drip and which may be adjusted and regulated to dispense the fluid automatically during predetermined periods of the day.

50 With these and other objects in view reference should be had to the accompanying drawing, in which

55 Figure 1 is a sectional view in elevation of a deodorizer and antiseptic dispenser embodying features of the present invention;

Fig. 2 is a cross sectional view in the direction of the arrows on the line 2—2 of Fig. 1;

Fig. 3 is a cross sectional view in the direction of the arrows on the line 3—3 of Fig. 1;

Referring more specifically to the drawing, the device shown therein preferably consists of an antiseptic fluid tank or reservoir 10, a dispensing unit or chamber 11, and a fumigating or air purifying element 12, which may be formed in separate units suitably arranged and attached together, or, as shown in the accompanying drawing, may be formed of a single tank 13 preferably formed of suitable metal and provided with horizontal partitions 14 and 15 dividing the tank into separate compartments.

The fluid tank or reservoir 10, as shown, is disposed between the horizontal partitions 14 and 15, the partitions preferably being formed of metal disks integral with or suitably secured to the inside walls of the tank. The disk 14 is provided with a central aperture or opening 16, a series of arcuate slits 17 concentric with the circumference of the disk, and a small opening 18 spaced from the central opening 16. Secured to the top of the disk 14 within the space defined by the arcuate slits 17, as by the screw 19, is a metal plate or disk 20, while formed integrally with the disk 20 is a cylindrical member 21 extending below and above the disk and preferably having an enlarged or trumpet-like top portion 22.

The member 21 serves as a filler pipe through which the antiseptic fluid may be poured into the reservoir or tank 10, and a suitable stopper may be provided in the filler pipe. In the present device an automatic stopper or closure is provided consisting of a floating ball 23 of lighter specific gravity than the fluid used in the tank and whose circumference is slightly smaller than the internal circumference of the pipe 21. An internal annular flange 24 is formed in the pipe 21 adjacent its central portion and preferably on a level with the top of the reservoir 10. The flange is of such a size as to provide a circular opening smaller than the circumference of the ball 23 and thereby prevent the passage of the ball beyond that point. The ball is inserted in the lower portion of the pipe 21 and a spider closure or slotted cap 25 is screwed or otherwise secured in the lower end of the pipe. The antiseptic fluid may then be poured into the trumpet-like end 22 of the pipe 21, and the ball 23 being smaller than the internal circumference of the pipe 21 will permit the fluid to pass into the reservoir 10.

As the reservoir 10 is filled, however, the ball 23 will float on the fluid and will 55

be forced up until it engages the annular flange 24, thereby closing the reservoir.

A suitable adjustable outlet is provided preferably at the bottom of the reservoir 10, and to this end the horizontal partition or disk 14 is provided with a threaded opening 26 into which is screwed a plug 27 which may be fitted with a suitable washer 28 and which may have a nut 29 threaded to its lower end. Formed through the plug 27 is a small duct or passageway 30 having an enlarged tapering top portion 31 into which the tapered valve 32 extends. The valve 32 is formed on the end of a relatively long rod or valve stem 33 having a threaded portion 34 extending through the internally threaded block 35 which is formed integrally with the plug 27. The rod or valve stem 33 extends upwardly, as at 36, through the aperture 18 formed in the partition or disk 14 and its upper end may be provided with a knurled handle or with a slot to receive a suitable tool so that the valve may be adjusted to permit the desired amount of fluid to escape from the reservoir through the outlet or duct 30.

To insure a flow of the fluid at a constant rate of speed regardless of the amount of fluid in the reservoir and to prevent the duct 30 from becoming clogged, a filter or wick 37 is preferably provided through which the fluid must pass to the duct 30.

As previously pointed out, the plug 27 has secured to its upper end a block 35 and this block in turn has a lateral extension 38. An L-shaped opening or chamber 39 passes through the extension 38 and block 35 and communicates with the enlarged end 31 of the duct 30. The filter 37 is secured over the end of the opening 39 and preferably comprises a perforated metal casing 40 secured at one end over the extension 38 and having suitable filtering means such as fibrous material or pieces of chamois 41 inside it and held in position as by means of the screen disks 42 fastened to the casing at both ends of the filter.

The dispensing unit or chamber 11 is disposed beneath the tank or reservoir 10, and preferably in the chamber a suitable timing and measuring unit is provided for receiving the fluid passing from the reservoir through the duct 30 and retaining the fluid for a certain predetermined length of time or until a certain predetermined amount of fluid has been accumulated, and then depositing the fluid in the chamber. The timing unit illustrated comprises a receptacle or pan 43 disposed beneath the duct or outlet 30 in the reservoir and pivoted adjacent one end as at 44 to brackets 45 secured to the base of the chamber 11. The receptacle is counterweighted along one edge as at 46, the counterweight being so disposed and of such a weight as normally to hold the receptacle in horizontal position if empty or return it to horizontal position if it has been pivoted from horizontal. The opposite edge of the receptacle is provided with a projecting lip 47 which engages a spring latch 48 so formed and of such a tension as normally to retain the receptacle in upright or horizontal position, but when the fluid in the receptacle increases in weight beyond a predetermined point the latch automatically releases the receptacle permitting it to drop down as shown in dotted lines in Fig. 1, thus emptying its fluid content into the dispensing chamber. When the receptacle or pan has thus been emptied it will automatically be returned to its normal horizontal position, engaging the spring latch, by means of the counterweight 46.

The spring latch is suitably secured adjacent one end as by means of screws 49 passing into a projecting block or lug 50 formed on the inside of the wall of the chamber 11. An adjusting screw 51 extends from the outside of the chamber through the side wall and engages the spring latch 48 above its point of connection with the wall of the chamber. Thus by means of the screw 51 tension on the spring latch 48 may be varied to permit automatic pivoting or emptying of the receptacle 43 when any desired amount of fluid has accumulated in it.

A disk 52 provided with an annular rim 53 threaded to the tank is secured over the bottom of the tank 13 and forms the bottom of the chamber 11. A washer 54 is preferably provided around the lower end of the tank to prevent fluid from escaping.

The disk 52 is provided with a small threaded opening 55 into which is screwed the externally threaded plug 56 having a duct or opening 57 extending from the inside of the tank through the plug 56, and a tube 58 communicating with the duct 57 is secured to or formed integrally with the plug 56. The tube 58 forms the dispensing tube through which the fluid is dispensed and accordingly is arranged so as to extend into the bowl or other device with which it is to be used.

The upper end of the duct tapers outwardly as at 59 and the adjustable tapered valve 60 secured to the end of valve stem 61 projects into this portion of the duct. The valve stem 61 is threaded to the top 62 of a filter 63 secured around the duct 57 and has an enlarged knurled top so that it may be conveniently adjusted. The filter preferably is composed of two concentric perforated metal disks having fibrous material or pieces of chamois disposed therebetween and suitably secured to the bottom 52 of the chamber around the opening 55. The top 62 of the filter, preferably formed of metal, is provided with a central threaded opening through which the valve stem 61 passes.

As pointed out above, a suitable air fumigating or deodorizing element is also provided at 12. The walls of this portion of the tank are perforated as at 64 and a tubular fabric wick 65 preferably disposed around a cylindrical metal frame or backing 66 is provided therein. The metal backing 66 is suitably secured to the horizontal partition or disk 14. The fabric wick is provided with three integral aprons or extensions 67 which project downwardly through the arcuate slots 17 provided in the disk 14 to approximately the bottom of the reservoir 10.

The tank 13 is preferably provided with fastening means to secure it to a wall, such as the brackets 68 having keyhole slots 69 therein which may be fitted over the heads of screws suitably fastened in the wall.

The operation of the device described is as follows: The tank is secured in the desired position with the dispensing tube 58 extending to the device to be disinfected and fumigated, and suitable antiseptic and deodorizing fluid 70 is introduced into the reservoir 10 through the pipe 21. When the reservoir is full the floating ball 23 will serve as a closure preventing the introduction of more fluid. The fluid passes through the filter 37, the opening 39, and the duct 27 into the receptacle 43, the flow of the fluid being controlled by the adjustment of the valve 32. Thus the valve may be adjusted so that only a slow intermittent dripping of the fluid will occur; or it may be opened wide to per-

mit a steady small stream of the fluid to pass through the duct 27. The receptacle 43 is at first held in horizontal position by the counter-weight 46 and spring latch 48. However, when 5 a predetermined amount of fluid has collected in the receptacle 43, depending upon the adjustment of the latch 48, the receptacle will pivot downwardly as shown in dotted lines in Fig. 1, permitting the fluid to escape into the dispensing chamber or unit. When the fluid has thus 10 been deposited into the dispensing chamber or unit, it will pass through the filter 63, through the duct 57 and the dispensing tube 58 to the device to be disinfected. The valve 32 and the 15 spring latch 48 may be so adjusted that the receptacle 43 will empty once a day, say in the morning, and the valve 60 may be adjusted to permit the fluid thus deposited in the chamber 11 to pass out of the chamber through the dispensing tube at a constant rate, say at a steady 20 drip, during daylight or office hours. Of course, the mechanism may be so adjusted as to permit the receptacle 43 to empty at any time of the day, or any number of times per day depending 25 upon the circumstances, and likewise, the amount of fluid so deposited at each emptying of the receptacle may be regulated and adjusted by means of the valve 32 and latch 38. In that way the dispensing of fluid at times when it is not 30 needed may be prevented. At all times the element 12 will operate to fumigate and deodorize the air, the fluid passing upwardly through the aprons 67 to the wick 65 and there evaporating into the air.

35 I claim:

1. In disinfecting apparatus, an automatic measuring device for delivering disinfecting fluid

periodically to a fluid dispensing unit, said measuring device comprising a fluid receptacle having a pivotal mounting so as to be shiftable from a horizontal fluid receiving position to an angular fluid depositing position, and means for holding 5 said receptacle in horizontal position until a predetermined amount of fluid is accumulated in said receptacle, said means including a counterweight at one end of the receptacle beyond the pivotal mounting, and a resilient automatically releasable 10 latch member having a fixed mounting adjacent the receptacle and positioned so as to engage the opposite end of the receptacle when it is in horizontal position.

2. In disinfecting apparatus, a reservoir for 15 a disinfecting fluid having a drip outlet formed in the bottom thereof, a dispensing chamber having a dispensing outlet formed therein disposed beneath said reservoir, and means for periodically delivering a predetermined amount of 20 disinfecting fluid from said reservoir to said chamber, said means comprising a fluid receptacle disposed beneath the outlet in the reservoir and having a pivotal mounting so that it can shift from a normal horizontal fluid receiving position to an angular fluid depositing position, and means for holding said receptacle in horizontal position until a predetermined amount of fluid has accumulated in the receptacle, said means comprising a counterweight 25 at one end of the receptacle beyond the pivotal mounting, and a resilient automatically releasable latch member mounted on the side of the dispensing chamber and positioned so as to engage the other end of the receptacle when it is 30 in horizontal position.

CORNELIUS W. O'REILLY.
